F. G. FARR

CONTROLLING VALVE FOR HYDRAULIC OIL STORAGE AND DISTRIBUTION SYSTEMS

Filed Feb. 9, 1922

FIG. 1.

FIG. 2.

INVENTOR.
FREDERICK G. FARR.

BY
Whittman Hubert Whittman

Patented Oct. 9, 1923.

UNITED STATES PATENT OFFICE.

FREDERICK G. FARR, OF NEW YORK, N. Y.

CONTROLLING VALVE FOR HYDRAULIC OIL STORAGE AND DISTRIBUTION SYSTEMS.

Application filed February 9, 1922. Serial No. 535,422.

To all whom it may concern:

Be it known that I, FREDERICK G. FARR, a citizen of the United States of America, residing at New York city, in the county of 5 New York and State of New York, have invented certain new and useful Improvements in Controlling Valves for Hydraulic Oil Storage and Distribution Systems, of which the following is a specification, reference being had therein to the accompanying drawings.

The invention relates to hydraulic oil storage and delivery systems and has particular reference to the construction of the 15 controlling valve, being an improvement upon my former Patent No. 1,286,971, dated December 10, 1918. It is the particular object of the present improvement to avoid the drainage of the displacement liquid 20 from laterally-extending portions of the conduit therefor, thereby avoiding the necessity of refilling such portions when delivery of oil is made. To this end the invention consists in the construction as hereinafter set forth.

In the drawings:

Figure 1 is a vertical central section through the valve;

Figure 2 is a section in a plane at right angles to Figure 1.

A is the valve casing which at one end is connected to the supply conduit B for the water under pressure and at its opposite end is connected to the drain conduit C. 35 D is a central chamber within the valve casing which is separated from end chambers E and F respectively connecting to the conduits B and C by ported partitions G and H. I and J are valves preferably of the 40 pocket type for controlling the ports in the partitions G and H and these valves are mounted on a common stem K by which when one valve is seated the other valve is withdrawn from its seat. L is an operating 45 lever which engages a yoke M on the valve J for actuating the same, said lever being fulcrumed at N and passing out from the chamber F through a slot O in the wall thereof. The construction as thus far described is essentially the same as that of my 50 former patent above referred to.

When the valve is connected into a hydraulic delivery system, the chamber D is connected with the conduit which extends to the bottom of the storage tank and 55 through which water is delivered for the

displacement of oil. Thus, whenever the lever L is raised to seat the valve J and unseat the valve I, water under pressure from the conduit B is delivered into the chamber D and through the connected conduit such as P extending to the storage tank. On the other hand, when the lever L is lowered, seating the valve I and unseating the valve J, the water is permitted to drain from the chamber D into the chamber F and drain conduit C. It frequently happens in the installation of such apparatus that the conduit P must extend laterally for a considerable distance before extending downward 70 to the bottom of the tank. Where this is the case with the construction of valve shown in my former patent, there is nothing to prevent the draining out of all of the water in the lateral portion of the pipe P, so that when the lever is reversed, it is necessary to refill this pipe before effecting displacement of oil from the storage tank. With my improved construction such defect is avoided by locating the ported partition H, through which communication is established, between the chambers D and F above the level of the conduit P. This will form a trap which will hold all of the water in the lateral portion of said conduit and will permit the drainage of water which is above the level of the partition. Therefore, whenever the valve I is opened, there will be a practically instantaneous delivery of water 90 through the conduit P into the storage tank, effecting a corresponding displacement of oil.

In order to obtain the desired relative location of the partition H and the conduit P, the latter is coupled to a portion Q of 95 the casing which extends downward at one side of the chamber F. This provides full area for the passage of the liquid and at the same time locating the conduit P below the partition H, as above described.

What I claim as my invention is:

1. A valve comprising a casing formed of a single piece of material having parallel alignment ported partitions dividing the same into inlet and outlet chambers and an intermediate chamber, a delivery connection to said intermediate chamber arranged below the level of the partition separating the same from said outlet chamber, and valves for alternatively closing the ports of said partitions.

2. A valve comprising a casing divided

by ported partitions into an inlet chamber in its upper portion, an outlet chamber in its lower portion and an intermediate chamber, valves controlling the ports in said partitions, a common valve stem for said valves alternatively seating the same, and a delivery connection for said intermediate chamber arranged below the level of the partition between said chamber and the outlet chamber.

3. A valve comprising a casing divided by separated ported partitions into an inlet chamber at its top, an outlet chamber at its lower end and an intermediate chamber for connection with a delivery conduit, and means within said valve casing for trapping the liquid in said delivery conduit from draining into said outlet.
4. A valve comprising a casing divided by separated ported partitions into an upper inlet chamber, a lower outlet chamber and an intermediate chamber for connection with a delivery conduit, valves having a common stem for controlling said ported partitions and alternatively seated thereon, and an extension of said intermediate chamber downward below the partition between the same and the outlet chamber to which said delivery

conduit is connected, forming a trap for preventing drainage of liquid below the top of said delivery conduit.

5. A valve comprising a casing having horizontally disposed ported partitions dividing the same into inlet and outlet chambers and an intermediate chamber, a delivery connection to said intermediate chamber arranged below the level of the partition separating the same from said outlet chamber, valves for alternately closing the ports of said partitions, and a common valve stem 40 for said valves.

6. A valve casing formed of a single piece of material having horizontally disposed ported partitions dividing the same into inlet and outlet chambers and an intermediate chamber, a delivery connection to said intermediate chamber below the level of the partition separating the same from said outlet chamber, valves for alternately closing the ports of said partitions, a common 45 valve stem for said valves, and means mounted within said outlet chamber for actuating said valve stem.

In testimony whereof I affix my signature.

FREDERICK G. FARR.
